UNITED STATES PATENT OFFICE.

GEORGE E. AVIS, OF NEW HAVEN, CONNECTICUT.

METHOD OF DRILLING AND REAMING BARRELS FOR FIREARMS.

1,177,983.

Specification of Letters Patent.

Patented Apr. 4, 1916.

Application filed June 21, 1915. Serial No. 35,218.

To all whom it may concern:

Be it known that I, GEORGE E. AVIS, a citizen of the United States, residing at New Haven, in the county of New Haven and State of Connecticut, have invented certain new and useful Improvements in the Method of Drilling and Reaming Barrels for Firearms, of which the following is a specification, reference being had therein to the accompanying drawings.

My invention relates to a new and improved method of drilling and reaming barrels for fire arms, and has for its object, among other things, to provide means for boring out a gun barrel in the shortest possible time, with the minimum waste of material.

To these, and other ends, my invention consists in the method of drilling and reaming barrels for fire arms, particularly set forth in the following specification and illustrated in the drawings accompanying the same, in which—

Figure 1 is a longitudinal sectional view of a gun barrel showing the same after it has been drilled; and Fig. 2 the same barrel after the reaming operation with the bore finished.

Heretofore it has been the practice to make the hole in a gun barrel with a drill that enters at one end and cuts the hole through the entire length thereof. This method has proven objectionable for many reasons, among others, being the fact that the drill does not run straight and is considerably out of true when it comes through the opposite end of the barrel. This necessitates the making of the rough barrel considerably larger than if the drill ran straight through, as the barrel is finished with the drilled hole as the center. The drill also frequently drills a hole that is bowed between its ends. This also must be guarded against, usually by using a drill smaller than would otherwise be desirable, as in every case the hole is reamed after being drilled and enough material must be left in the rough barrel to provide a smooth and straight hole or bore from end to end.

With the method above described, having the objections indicated, as well as many others, the drill works only from one end of the barrel, and hence much time is required to perform the drilling operation; the drill is much longer than the barrel itself, and by reason thereof it is impossible to

drill a straight hole its entire length; and again, as the rough barrel must be made sufficiently large to provide for the imperfect drilling thereof and be finished with the drilled hole as the center instead of the actual center of the rough barrel, much material and time is thereby wasted.

I have overcome all of these objections in my improved method by forming the rough gun barrel of substantially its completed size and shape, leaving only sufficient stock thereon for a finishing cut after the hole is bored, and in some cases, with some barrels, even this is not necessary, by using a plurality of comparatively short drills, which are fed into the barrel from both ends at the same time, and afterward withdrawn and two new drills substituted of slightly smaller diameter. These operations are continued with drills of progressively smaller diameter until they meet in the longitudinal center of the barrel, after which the drilled hole is reamed out to its finished size.

In the drawings, the numeral 1 designates the gun barrel, and in Fig. 1 the same is shown after it has been drilled, the holes 2—2 being the first ones bored, followed successively by the holes, 3—3, 4—4, 5—5, 6—6 and 7—7, each being slightly smaller in diameter than the preceding hole. The difference in the diameters of these holes is exaggerated in the drawing for the purpose of clearness in illustration. In practice they differ in diameter not more than one-thousandth of an inch, or slightly more, if desired.

It is almost impossible to have a drill run straight and true in drilling out a gun barrel, but in my method if the drill does run out of true, the extent of its inaccuracy will be just one-half of what it would be under the old method, as the hole only extends half way through the barrel instead of through its entire length and the greatest offset is near the center of the barrel where the diameter of the holes is the smallest and there is sufficient material for the reamer that passes through the barrel to produce the finished bore.

With my method the drills are comparatively short and hence the liability to break or spring is reduced to the minimum, and as the barrel is bored from both ends at the same time, the amount of time required to drill it is very materially reduced; inaccuracy of the drilled hole is near the longi-

tudinal center of the barrel where the holes are the smallest in diameter; each successive drill is guided in the hole made by the preceding drill, and being of slightly smaller diameter the probability of its traveling out of its true line is reduced to the minimum; and again, the hole being drilled from both ends concentric with the barrel itself, permits the rough barrel to be made substantially the same size and shape as the finished barrel, thereby saving material and labor in the finishing process.

Having described my invention, what I claim as new and desire to secure by Letters Patent, is:—

1. A new and improved method of drilling barrels for fire arms, consisting in drilling the barrel from both ends by a suc-

sion of drills of progressively smaller diameter.

2. A new and improved method of drilling barrels for fire arms, consisting in drilling the barrel from both ends at one and the same time by a succession of drills of progressively smaller diameter.

3. A new and improved method of drilling and reaming barrels for fire arms, consisting in drilling the barrel from both ends at one and the same time by a succession of drills of progressively smaller diameter and reaming the drilled holes so as to produce a straight hole of uniform diameter.

In testimony whereof I have hereunto affixed my signature.

GEORGE E. AVIS.
